UNITED STATES PATENT OFFICE.

JOHN K. HOWE AND JAMES CLARK, OF ALBANY, NEW YORK.

ENGINE FOR OPERATING CLUTCHES OR OTHER DEVICES.

SPECIFICATION forming part of Letters Patent No. 530,994, dated December 18, 1894.

Application filed June 6, 1894. Serial No. 513,666. (No model.)

To all whom it may concern:

Be it known that we, JOHN K. HOWE and JAMES CLARK, both of Albany, in the county of Albany and State of New York, have invented new and useful Improvements in Engines for Operating Clutches or other Devices, of which the following is a specification.

Our invention relates to improvements in clutch-operating mechanisms for machines in which it is necessary to suspend, and restore to action, certain functions of parts of the machine without interfering with the operation of other parts, and the object of our invention is to provide facilities for operating clutch-mechanisms, but especially friction-clutch mechanisms, with such ease, promptitude and positiveness that they can be relied upon with certainty and safety, and by which the force applied to a friction-clutch can be varied or graduated to any point between a minimum and a maximum force required to operate the clutch; said graduation being effected by moving an operating-lever through a lesser or greater arc, as in hand-operated clutch-mechanisms. This object we attain by the mechanism illustrated in the accompanying drawings, which are herein referred to and form part of this specification, and in which—

Figure 1 is a combined longitudinal section and side elevation of the steam-cylinder and its connected parts; Fig. 2, a vertical section of Fig. 1 at the irregular line X X; Fig. 3, an enlarged and detached longitudinal section of the tubular valve, showing the auxiliary piston for the same in side-elevation; Fig. 4, a plan view of a portion of a lever for transmitting power to the clutch-mechanism; Fig. 5, a front elevation of the trunnion-block for said lever; Fig. 6, an end elevation of the same; Fig. 7, a side elevation of our invention applied to the friction-clutch of a hoisting-drum; and Fig. 8, a side elevation of our invention applied directly to the screw of a clutch-operating mechanism.

In many machines, wherein it becomes necessary that the operation of some of the parts should be suddenly suspended, and as suddenly resumed, it is frequently found that manually-operated clutch-mechanisms are

inefficient for performing the work in a prompt and satisfactory manner, and this defect is most frequently observed in large machines and where the work to be performed is heavy.

As represented in the accompanying drawings, A designates the main cylinder for our clutch-operating mechanism; the outer end of which is designed to remain open, but the opposite end is provided with a head, B, which forms a closure for the same. Superimposed on the cylinder A, there is an auxiliary cylinder, C, which is arranged to form a valve-chest, as hereinafter explained, and, leading from near the middle of the latter and extending to the inner end of the cylinder A, there is a passage, D, for conveying steam, or other fluid, into the main cylinder.

E is a piston fitted to move in the cylinder A, and said piston is provided with a suitable packing, F, for forming a tight joint with the bore of said cylinder. Said piston is also provided with a lug, G, or other suitable means, for affording a connection from said piston with the mechanism to which it is directly connected. The outward stroke of the piston E is effected by a direct pressure of steam, or other fluid, against the inner face of said piston. The return stroke of the latter is effected in the manner hereinafter explained, and, for the purpose of providing against a possible impact of the piston with the head B, a buffer-spring, 1, is arranged in a chamber, 2, formed for that purpose in the head B, but, when preferred, said spring may be omitted.

H is a tubular valve fitted to move in the bore of the auxiliary cylinder C; the opposite extremities of said valve being alone fitted to fill the bore of said cylinder, so as to form a fluid-tight joint therewith, the intermediate portion of said valve—between said extremities—being reduced in diameter so as to leave an annular opening, 3, between the valve and the bore of the cylinder C, and said opening is always in free communication with the passage D, and, leading from the interior of the valve H into said annular opening, there is a circumferential row of openings, 4, through which steam, or other fluid, can pass from the bore of said valve, thence through the annu-

lar opening 3 and passage D, into the main cylinder A. The inner portion of the bore of the valve H is enlarged, to form a shoulder, h, for a purpose hereinafter explained, and the corresponding end of said valve has a head, 5, secured therein, and said head is provided with one or more openings, 6, whose purpose will be explained herein. Extending centrally from the head 5, there is a stem, 7, which—after passing through a stuffing-box, 8, formed on a head, 9, that forms a closure for the corresponding end of the cylinder C—is provided with a lug or lugs, 10, detachably attached thereto.

15 I is an operating-lever which is fulcrumed, as at 11, to a bracket, 12, and is connected—by links, 13, to the lug 10, for the purpose of imparting suitable movements to the valve H. At the foremost end of the auxiliary cylinder 20 C, an induction-pipe, 14, is arranged to communicate with the bore of said cylinder for the purpose of conveying a supply of steam, or other fluid under pressure, into the cylinder C; and at the opposite end of the latter 25 an ejection-pipe, 15, is arranged to conduct the spent steam, or other fluid, from the cylinder C.

J is a piston fitted to form a steam-tight joint with the bore of the tubular valve H; 30 said piston should be of sufficient length to cover the openings 4 and form a lap at the opposite sides of said openings, as illustrated in Fig. 1. Extending centrally from the piston J, there is a piston-rod, 16, which passes through a stuffing-box, 17, on a head, 18, that forms a closure for the forward end of the cylinder C, and the outer end of said piston-rod is provided with a lug, 19, which is detachably attached thereto.

40 K is a lever secured to a shaft, 20, journaled in a frame-work, 21, so as to receive an oscillating motion therein; said lever has a pendant arm, 22, whose lower end is connected—by a connecting-rod, 23—to the piston E, so that the movements of said piston will be transmitted to the lever K. The piston-rod 16 is connected—by links, 24—to the arm 22 at a point intermediate between the shaft 20 and the point whereto the connecting-rod 23 45 is connected.

As shown in Fig. 1, the lever K is of a bell-crank form—but our invention is not limited to that particular form of lever, for it is obvious that any other form will be equally good for our purpose—and it has a horizontal arm, 25, that is bifurcated to receive a trunnion-block, 26, having oppositely-located trunnions, 27, ranging in line with each other and fitted to engage in notches, 28, formed in the arm 25, so as to vary the distance between the centers of said trunnions and of the shaft 20 when occasion may require. Cheek-plates, 29, which are detachably secured to the arm 25, are fitted to receive the outer ends of the trunnions 27 and retain the latter in the notches 28. The trunnion-block 26 is provided with an opening, 30, in which

is fixed a rod, 31, whose upper end is provided with adjusting-nuts, 32, for regulating the length of said rod as occasion may require. Said rod may be connected in any suitable manner to a clutch-mechanism.

As shown in Fig. 7, the rod 31 connects with a pair of levers, 35 and 36, of unequal length and arranged to form a species of “toggle-joint.” One end of both of said levers is jointed to the rod 31, the opposite end of the lever 35 being fulcrumed to a lug, 37, formed on a pillow-block, R, in which one end of a drum-shaft, S, is journaled. One end of the lever 36 is jointed to the movable end of a lever, 38, fulcrumed to the pillow-block R, and the differential movements of the levers 35 and 36 will cause the upper end of the lever 38 to move toward the pillow-block R with powerful effect. An adjustable-bolt, 40, is inserted in the lever 38 and arranged to bear against the outer end of a pin, 41, which is centrally placed in the shaft S so as to move loosely therein. The inner end of said pin is fitted to bear against a transverse gib, 42, loosely fitted in said shaft and arranged to bear against a loose collar, 43, having a sliding movement on the shaft S. The inner face of the collar 43 is fitted to bear against a hub of a hoisting-drum, Q, which is loosely fitted on the shaft S and is provided with one part of a friction-clutch, 44, of an old and well-known form which forms no part of our invention. T is a gear-wheel that is secured 100 to the shaft S and is provided with a complementary part, 45, of said friction-clutch; the parts 44 and 45 being fitted to frictionally engage with each other—when the drum Q is forced into connection with the gear-wheel 105 T—so that said wheel, shaft, and drum will operate as one piece.

Our invention, as above described, operates in the following manner: Steam, or other fluid under pressure, is admitted into the auxiliary cylinder C, through the induction-pipe 14, while the piston J is in position to cover the openings 4, and, in order to prevent the valve H from being prematurely moved by the inflowing fluid, the operating-lever I should be securely held in a position where its openings 4 will be safely closed by the piston J. Then, by moving the valve H toward the induction-pipe 14, the openings 4 will be uncovered to allow the fluid-pressure 120 to pass through them into the annular-opening 3, and thence, through the passage D, into the inner end of the cylinder A, where its force will be exerted to drive the piston E toward the outer end of said cylinder. By 125 this movement of the piston E, the lever K will acquire a corresponding movement to draw the rod 31 upwardly, and the levers 35 and 36 will be operated to force the two parts of the friction-clutch together so that the 130 drum Q will be rotated by, and with, the gear-wheel T. To disengage the parts of the friction-clutch, the valve H should be moved—by the operating-lever I—toward the educ-

tion-pipe 15, thereby preventing the openings 4, either partially or entirely, from being closed by the piston J, and so that said openings will lie between said piston and the 5 eduction-pipe 15. By this movement of the valve H the pressure in the cylinder A will be dissipated—either suddenly or gradually, according to the degree to which the uncovering of the openings 4 is effected—by the steam, 10 or other fluid, escaping from the cylinder A through the passage D, into the annular-passage 3, thence through the openings 4 into the valve H, and thence, through the openings 6 and auxiliary-cylinder C, into the eduction-pipe 15, from whence it may be discharged 15 into the atmosphere or other suitable place. By the last described movement of the valve H, the shoulders h, of said valve, can be carried into contact with the outer face of the 20 piston J, and the power applied to the operating-lever I, will supplement by the pressure acting against the outer face of the piston J, to impart an initial movement to the lever K to move the piston E inwardly in the 25 cylinder A and effect a separation of the two parts of the friction-clutch.

In the modification of our invention shown in Fig. 8, which is also designed for operating friction-clutches of the class which has 30 its movable part moved into, and out of, gear with the other part by means of a screw or other similar means, L designates the mechanism (hereinbefore described for operating the bell-crank lever K of Fig. 1), connected 35 to an arm, M, which is attached to the outer end of a screw, N, arranged to move the movable part of a friction-clutch, and, for the purpose of obtaining a quick movement of said movable part, said screw is preferably made 40 multi-threaded in the usual manner of making such screws. For the purpose of affording a ready adjustment of said screw in respect to said movable part, the arm M is provided with a split hub, 33, having a clamp-screw 34, arranged to draw the two parts 45 of said hub toward each other so as to securely clamp the arm M to the screw N after said arm has been adjusted to a required position on said screw. The main-piston and 50 auxiliary-piston (hereinbefore described in respect to Fig. 1), pertaining to the mechanism L, are relatively connected to the arm M in the same manner that the like parts are connected to the bell-crank of Fig. 1. O is the 55 housing for a hoisting-drum, which is substantially the same as the one shown in Fig. 7; said drum being rotated by means of a spur-wheel and pinion—indicated by dotted lines in Fig. 8. P is the movable part of the 60 friction-clutch, which is substantially the same as the one hereinbefore described, and which is moved into, and out of, gear with the complementary part of said friction-clutch which is attached to the spur-wheel.

65 In the modification of our invention just described, the arm M is connected to the main- and auxiliary-piston of the operating

mechanism in the manner hereinbefore described in respect to their connection with the bell-crank lever K.

In either form of our invention, when it is essential to apply sufficient force to retain the parts of a friction-clutch in such a condition of contact that there can be no slipping of said parts, the valve H should be moved forward to the full extent of its intended travel, whereby the piston E will be forced forward to effect the required end, and this condition can be maintained as long as the openings 4 remain open for the admission of steam or 80 other fluid-pressure. If, however, it is only necessary to apply sufficient force to allow the parts of the friction-clutch to slip upon each other with more or less freedom, the valve H should be moved forward far enough 85 to slightly uncover the openings 4, from the piston J, and the admitted pressure, acting upon the piston E to move the latter outward, will carry the parts of the friction-clutch into contact, and the time of such contact and its 90 degree can be regulated by the movement of the valve H by means of the operating-lever I. By the outward movement of the piston E the piston J will be moved forward to close—either partially or entirely—the openings 4, 95 and it is obvious that, by slight movements of the valve H in the required directions, the pressure on the friction-clutch can be increased or diminished as occasion may require. When the friction-clutch is to be operated as a brake, while a weight is pendent on the hoisting-drum, the valve H should be moved inwardly to allow the openings 4 to communicate with the eduction-pipe 15, said 100 openings being but slightly uncovered for 105 this purpose, and the pressure acting against the inner face of the piston E will be reduced proportionately to the opening afforded for the escape of the pressure and the time that is allowed for such escape, for it should be 110 understood that this escape can be checked instantly by a proper movement of the valve H, but, while such pressure is escaping, the pressure on the outer face of the piston J will 115 force the piston E inwardly, and this inward movement will continue until the piston J closes the communication between the openings 4 and the eduction-pipe 15, whereupon 120 the pressure confined in the cylinder A will forcibly hold the parts of the clutch in sufficient frictional contact to allow an operative 125 to retain command of the suspended weight, and, as hereinbefore stated, the pressure can be either augmented or diminished, by proper movements of the valve H; and it will readily be seen that the point at which the movement of the pistons E and J will terminate in either direction—by the closing of the openings 4—will be determined by the position of 130 the lever I in the hands of the operator, and that the degree and direction of the movement of the piston E will correspond exactly to the degree and direction of said lever, as in hand-operated friction-clutches.

While we have shown and described our invention as applied to operating clutch mechanisms, we do not limit it to such uses, for it can be applied without further invention as a means for operating many different kinds of mechanisms.

What we claim as our joint invention, and desire to secure by Letters Patent, is—

1. The combination of a main-cylinder, an auxiliary-cylinder connected to said main-cylinder by means of a passage communicating with the bores of both of said cylinders; each of the latter being provided with a piston connected to a lever or arm that is common to both pistons, and the auxiliary-piston being arranged in such manner that only one of its ends will be exposed to the pressure of live steam, and a manually-operated tubular-valve for controlling the admission and emission of steam into and out from said main-cylinder; whereby the main-piston will be moved in one direction by pressure acting directly upon said piston, and in the opposite direction by pressure applied directly against the auxiliary-piston and transmitted—by means of said lever or arm—to the main-piston, as and for the purpose specified.
2. The combination of a main-cylinder having a piston fitted to reciprocate therein; an auxiliary-cylinder ancillary to said main-cylinder and provided with an induction-pipe—which leads into one end—and an eduction-pipe leading from the opposite end of the same, a tubular-valve fitted to slide in the bore of the auxiliary-cylinder and having its periphery arranged to form an annular-passage between said valve and the bore of the auxiliary-cylinder; said annular-passage forming a constantly-open communication with a passage leading into the bore of the main-cylinder, an opening or openings leading from the bore of said valve into the annular-passage, a piston fitted to move in the bore of said valve and arranged to govern the openings of the latter into the annular-passage, a manually-operated lever connected to said valve, and an arm or lever to which the main-piston and auxiliary-piston are both connected, as and for the purpose specified.
3. The combination of a main-cylinder pro-

vided with a piston fitted to reciprocate therein, an auxiliary-cylinder provided with a passage that leads into the main-cylinder, a tubular-valve which controls the admission and emission of steam into and from said main-cylinder; said valve being counterbored to form a shoulder near the middle of the valve, an auxiliary-piston fitted to reciprocate in the larger bore of said valve, a lever or arm connected to both of said pistons, and an operating-lever connected to said valve; whereby the latter can be moved so that its shoulder will take against the auxiliary-piston to effect an initial inward movement of the main-piston, as and for the purpose specified.

4. The combination of a main-piston, an auxiliary-piston, a lever or arm to which both of said pistons are connected; both of said pistons being arranged to move in unison, and a buffer-spring arranged to receive the impact of the main-piston, as and for the purpose specified.

5. The combination of a manually-operated valve, a piston fitted to move reciprocally in said valve, and openings formed in said valve; whereby said openings can be automatically closed by said piston while the latter is moving in either direction, as herein specified.

6. The combination of a cylinder, a tubular-valve whose extremities are fitted to the bore of said cylinder and whose body is reduced in diameter to form an annular-passage between said body and the bore of the cylinder; one end of said valve being open and the opposite end being provided with a head containing an opening or openings; the body of said valve being provided with an opening or openings which lead from the bore of the valve into said annular-passage, and a piston fitted to reciprocate in the bore of said valve; said piston being arranged to automatically close the openings leading from the bore of the valve into said annular-passage, as and for the purpose specified.
